JOHN T. LOCKWOOD, OF NEW YORK, N. Y.

SPACE-BAND FOR COMPOSING-MACHINES.

1,113,362.

Specification of Letters Patent.

Patented Oct. 13, 1914.

Application filed April 21, 1913. Serial No. 762,447.

To all whom it may concern:

Be it known that I, JOHN T. LOCKWOOD, a citizen of the United States, and a resident of the borough of Brooklyn, city of New York, county of Kings, and State of New York, have invented certain new and useful Improvements in Space-Bands for Composing-Machines, of which the following is a specification.

10 My invention relates to space bands for composing machines, especially for linotype machines. Space bands are used to justify the lines of matrices and to lock them up during the casting of the slugs, after which 15 they are generally returned to a magazine and used over and over again.

The principal object of my invention is to provide a space band which may be made at a much lower cost than heretofore. Heretofore space bands have been individually shaped and finished from a solid bar of steel; and their manufacture entailed considerable machine work because they must necessarily be accurate in shape and proportions. Inasmuch as space bands are extensively used and have to be replaced from time to time as they become worn or broken, their cost of manufacture is an important factor in the art. Under my invention the 25 wedges, which constitute the more expensive part of the complete band, may be made by a stamping method, by cutting a blank of sheet metal in a suitable cutting die and then shaping it in a forming die. When 30 shaped, the wedges may be ground on their opposite faces and edges to reduce all the wedges to a uniform thickness and a uniform width. When the wedges are shaped as herein shown and described, they will be 35 rigid and strong enough to serve their purpose and, in fact, will be equally as durable as space bands now made by the more expensive methods. There is a saving not only in the cost of the wedge, but in the entire 40 space band, because it is not necessary under my invention to form a dovetailed connection between the slide and wedge by the expensive planing method. These results 45 are attained by stamping the wedge with 50 longitudinal corrugations.

In the drawings forming part of this application, Figure 1 is an enlarged perspective view, showing, in the preferred form, a complete space band made in accordance 55 with my invention, Fig. 2 is a face view thereof, on an enlarged scale, showing the

face opposite to that shown in Fig. 1, Fig. 3 is an end view thereof, on an enlarged scale, looking at the left hand end of Fig. 2, Fig. 4 is a cross sectional view, taken on the line 4-4 of Fig. 2, Fig. 5 is a sectional view, on an enlarged scale, taken on the line 5-5 of Fig. 2, and Fig. 6 is a side elevation.

The space band 1, consists of a wedge 2 and a slide 3, which are here shown as 65 formed to conform to the requirements of the composing machines now in general use; but it is to be understood that changes may be made therein to make the device suitable for other kinds of composing machines; and 70 I therefore desire it understood that the following detailed description is not intended to limit the scope of my invention to this exact form.

The wedge 2 is formed of sheet metal 75 which is preferably of equal thickness throughout, at least before the wedge is ground as hereinafter set forth. The wedge has the usual longitudinal slot in which the holding member of the slide moves; and on 80 either side of this slot the wedge is corrugated, the corrugations extending lengthwise thereof. The broad feature of my invention resides in the fact that the wedge is corrugated lengthwise, so that, though 85 stamped and drawn up from sheet metal, it will have sufficient lateral strength and rigidity to meet requirements. The longitudinal grooves formed by the corrugation of the metal are preferably defined by 90 tangentially arranged, flat walls.

In the drawings, the wedge 2 has a flat web 4 which lies flush with one side of the wedge; and lengthwise thereof there is a slot 5 as above referred to; while, at one end 95 there is a V notch 6 corresponding to the usual V shaped end of the slide where the latter straddles the distributor bar; and at the opposite end of the web there is the usual slot 7.

The web 4 is here shown as of uniform width throughout. From the web 4 the metal plate bends at an angle therefrom, preferably at right angles, on each side thereof, to form walls 8, 9, which tend to 105 make the wedge rigid laterally and to give it the desired shape and proportions. The walls 8, 9 are similar and preferably parallel; and decrease in depth from the bottom 10 of the wedge toward the top or entering 110 end 11; and, in fact, they may totally disappear near the top of the wedge.

At the edges of the walls 8, 9 opposite the web 4 the metal plate turns, preferably at right angles, and forms the webs 12, 13, which extend laterally in opposite directions, and in the same plane. These walls 12, 13 are preferably of uniform width throughout and constitute the opposite face of the wedge to the web 4. At the outer edges of the webs 12, 13 the plate turns upwardly, preferably at right angles thereto, forming the vertical walls 14, 15 which are preferably parallel with each other and terminate in the free edges 16. The walls 14, 15 decrease in height from the bottom 10 of the wedge toward the top 11, where they may entirely disappear or terminate as flat metal. At the bottom of the wedge the walls 14, 15 preferably turn inwardly at 17 and merge with the web 4.

20 The slide 3 is somewhat similar to the ordinary slide, it having the usual teeth 18 for engagement with the elevator and distributing bar of the composing machine; as well as the middle notch 19 where it 25 straddles the combination of the distributor bar. The slide contacts with the face of the web 4 and the edges 16 of the walls 14, 15; and it has an extended shoulder 20 which passes through the slot 5. On the surface 30 of this shoulder there is secured a block 21, preferably by means of a rivet 22 passing through the block and slide. The block 21 is of greater width than the slot 5 and it travels against the opposite face of the web 35 4 to that of the slide. I prefer to make this block sufficiently wide to contact with the inner faces of the walls 14, 15. It has a movement lengthwise of the wedge, equal to the length of the slot 5.

40 By constructing the device as herein shown, it is unnecessary to provide a dovetail connection between the block 21 and wedge, as is customary under the present expensive method.

45 After the wedge has been formed it may be ground on both faces to make it smooth and so that all wedges may be reduced to equal dimensions. It may also be ground upon its opposite edges, *i. e.*, along the outer 50 faces of the walls 14, 15 to make them smooth and to reduce all wedges to the same width. The grinding will also sharpen the edges 23.

55 The space band may be used in exactly the same manner and on the same machines as space bands now in use and they are, in fact, interchangeable therewith; and therefore a description of their use need not be set forth herein.

60 From the above it will be apparent that the wedge is corrugated lengthwise, thereby permitting the same to be made sufficiently strong and rigid and by a stamping process, and this constitutes the broad feature of 65 my invention. The longitudinal corruga-

tions are of decreasing depth, so that the device is wedge shaped.

The walls 8, 9 and web 4 form a groove or pocket 24 within the confines of which the block 21 may travel and be held; and 70 this groove is preferably open to one face of the wedge. The walls 9, 13 and 15 on the other hand form a longitudinal groove 25 which is preferably open to the opposite face of the wedge to that of groove 24. The walls 8, 12 and 14 also form a longitudinal groove 26 which is preferably open to the same face of the wedge as the groove 25. The walls 8, 9, 14 and 15 make the wedge rigid laterally, or in its smaller dimension, 80 thereby making it sufficiently strong and rigid for its purpose.

Having described my invention, what I claim is:

1. A wedge for space bands drawn up 85 from sheet metal of uniform thickness to form corrugations extending longitudinally of the wedge, for the purpose set forth.

2. A wedge for space bands, drawn up 90 from sheet metal of uniform thickness to form corrugations extending longitudinally of the wedge, for the purpose set forth, said corrugations decreasing in depth longitudinally of the wedge.

3. A wedge for space bands, drawn up 95 from sheet metal of uniform thickness to form corrugations extending longitudinally of the wedge and to form longitudinal grooves, said grooves being defined by side walls arranged perpendicular to the face of 100 the wedge.

4. A wedge for space bands, drawn up 105 from sheet metal of uniform thickness to form corrugations extending longitudinally of the wedge and to form longitudinal 110 grooves, said grooves being defined by side walls arranged perpendicular to the face of the wedge and decreasing in height longitudinally of the wedge.

5. A wedge for space bands, drawn up 110 from sheet metal of uniform thickness to form corrugations extending longitudinally of the wedge, said wedge having spaced 115 face webs connected by intermediate perpendicular walls, said wedge having outer side walls.

6. A wedge for space bands drawn up from sheet metal to form longitudinal corrugations, and comprising a medial face web 4, laterally extending walls 8, 9, forming 120 therewith a groove opening to the face of the wedge opposite the plate 4, face webs 12, 13, and lateral walls 14, 15, terminating flush with the web 4.

7. A space band, comprising a slide and 125 a wedge, said wedge being drawn up from sheet metal of uniform thickness to form corrugations extending longitudinally thereof forming a groove extending longitudinally of the wedge, said slide having a re- 130

taining member traveling within said groove.

8. A space band comprising a slide, and a wedge, said wedge being drawn up from sheet metal of uniform thickness and corrugated longitudinally of the wedge to form a longitudinally extending groove, said wedge having a longitudinally extending slot, said slide having means extending through said slot and a retaining block traveling in said longitudinal groove.

9. A space band comprising a slide, and a wedge corrugated longitudinally and comprising a face web, said slide engaging one

side of said face web and extending through 15 said face web and having a retaining member engaging the opposite face of said web, other face webs spaced from said first web and connected therewith by intervening walls, forming a groove within which said 20 retaining member travels, and outer side walls.

Signed at the city, county and State of New York, this 19th day of April, 1913.

JOHN T. LOCKWOOD.
